Attorneys

UNITED STATES PATENT OFFICE.

LOUIS V. ARONSON, OF NEWARK, NEW JERSEY.

SPARKING RATTLE.

Application filed February 6, 1924. Serial No. 691,002.

To all whom it may concern:

Be it known that I, LOUIS V. ARONSON, a citizen of the United States, residing at Newark, in the county of Essex and State of New Jersey, have invented certain new and useful Improvements in Sparking Rattles, of which the following is a specification.

The invention relates to toys of the "watchman's rattle" type wherein means are provided to produce sparks when the device is operated, which means are constructed to provide a series of relative movements between the sparking element and the revoluble element which exceed in speed those caused by the normal revolution of the rattle.

A further object of the invention is to improve the construction of the "watchman's rattle" type of toy.

Further objects of the invention will appear from the following description when read in connection with the accompanying drawing, wherein

Fig. 1 is a side elevation of the device.

Fig. 2 is a front elevation.

Fig. 3 is a central detail section through the revoluble disk and

Fig. 4 is a horizontal transverse section on line 4, 4 of Fig. 2.

As shown, the device comprises a handle 10, carrying a weighted disk 11 at one end. The handle is desirably formed as shown by pressing a blank to provide a body plate 12 and side members 13, 14 having disk shaped elements 15, 16 at one end between which the weighted disk 11 is shown as secured, as by means of a screw bolt or rivet 17. At the remaining end of the side members 13, 14 there is journaled a shaft 18 preferably squared at the end bearing the handle 19. The end of the shaft 18 which is journaled in the end of the side 14 is shown as formed cylindrically with a shoulder at 20 where the squared portion ends.

To cause sound of the rattle a star wheel 21 is shown as seated against the shoulder 20, the opening in the interior of the star wheel being square to fit over the squared portion 18. To preserve the spacings of the ends 13, 14 short sleeves 22, 23 are shown as mounted upon the shaft 18 between the star wheel and the ends of the members 13, 14.

A disk 24 is shown rigidly secured to the end of the shaft 18, as by means of a reduced portion upon the shaft 18 passed

through the center of the disk and headed at 25. To produce sparks in a manner to be described, the face of the disk is shown as bearing a disk 26 of abradant material. 60

The disk 26 is preferably secured to the disk 24 in the manner shown, as by crimping the edge 27 of the disk 24 about the disk 26. To produce sound when the rattle is operated, a tongue 28 is shown fitting between the frame members 13, 14 and having projecting studs 29, 30 journaled in ears 31, 32 carried by the members 13, 14.

A stop member for the tongue 28 is desirably formed, as shown, by the inturning 70 of the end 33 of the plate portion 12 of the frame 10 of the device. To press the tongue 28 normally against the stop member 33 the end 34 thereof is turned so as to project to the interior of the frame and a spiral 75 spring 35 is connected to a tongue 36 formed thereon and anchored to a second tongue 37 formed upon the lower inturned end 38 of the plate member 12.

To produce sparks when the device is operated, there is shown an arm 39 desirably formed from the same blank with the tongue 28 by turning a portion thereof at an angle to said tongue and shown as projecting parallel with the tongue to a position 80 adjacent the disk 24. To preserve the relation between the arm and the disk the end of the arm 40 is desirably turned about the disk as shown particularly in Fig. 2. A pyrophoric element 41 is shown as mounted 90 in a cylinder 42 and forming a loose fit therewith, the cylinder being carried by the arm 40. To provide pressure upon the element, a spring 43 is shown mounted upon tongues 44, formed from projecting portions 95 of the material of the arm 39 turned to a position such that portions of the tongues stand in spaced relation to the arm and extend to the interior of the coiled portion 45 of the spring. The anchor end of the 100 spring 46 is shown as impinging against the surface of the arm 29 and the pressure exerting end as projecting into a slot 47 in the cylinder 42.

When the device is operated the handle 105 19 will be grasped rigidly by the user and the weighted end 11 of the device swung thereabout in the well understood manner. The handle and the star wheel 21 will therefore remain stationary while the body of 110 the device with the arm 39 are revolved with relation thereto. This revolution must

be in the direction of the arrow in Fig. 1, and such revolution when the star wheel impinges against the tongue 28 will cause relative movement of the arm 39 still in the direction of the arrow as regards the disk 24. The actual relative movement between the pyrophoric element and the abradant material while the tongue 28 is being retracted against the pressure of spring 35 will be the sum of the movement caused by the body of the device and the retracting movement of the tongue as participated in by the arm 39, thereby producing a movement substantially twice the normal velocity. When the tongue 28 escapes from one point of the star wheel 21 the spring 35 will restore the tongue 28 and arm 38 to normal, thereby causing a very quick retrograde movement of the pyrophoric element in the same direction as the movement of the relative revolution of the disk thereto but at much greater speed. The result of the action described will be an increased shower of sparks due to the increased relative movement.

The movement of the pyrophoric element relative to the disk, due to the action of the star wheel upon the tongue 28, will be in an arc having its center at the lug 30. The path of movement will therefore be that indicated by the dotted line 48, Fig. 1. Therefore, the portion of the abradant material which acts upon the pyrophoric element will comprise a zone instead of a circle concentric with the center 25 of the disk, thus prolonging the useful life of the sparking mechanism.

Minor changes may be made in the physical embodiment of the invention without departing from its spirit.

I claim:

1. A sparking rattle comprising, in combination, a handle, a stationary rattle member rigidly carried thereby, a weighted revolute element mounted thereon, a spring retracted rattle member carried by said weighted element, a disk carried by one of said members, an abradant surface upon said disk, a pyrophoric element carried by

the remaining member, means for pressing said pyrophoric element against said abradant surface, whereby normal relative movement between said pyrophoric material and said abradant material caused by revolution of the weighted element is increased by movement of the rattle member.

2. A rattle comprising, in combination, a body formed from a blank and comprising a plate member, side frame members provided by bending the blank at the margins of said plate member, a weight secured between adjacent ends of said side members, a handle, a shaft rigidly secured to said handle and journaled between the remaining ends of said side portions, a star wheel rigidly secured upon said shaft, a rattle tongue journaled between said side members, a stop member formed from said body blank by turning an end of said plate between the handle carrying ends of said side members, at much greater speed. The result of the means for resiliently pressing said tongue against said stop in a position to project between the arms of said star wheel whereby revolution of the weighted body may cause retraction and return to normal of

75 3. A sparking rattle comprising, in combination, a swinging body having a weighted extremity, a handle, a shaft rigidly carried by said handle and journaled in the axial 80 portion of the abradant material which acts upon the pyrophoric element will comprise a zone instead of a circle concentric tongue projecting normally between the arms of said star wheel, a stop upon said tongue against said stop, a disk rigidly carried by said shaft, abradant material upon the surface of said disk, an arm rigidly secured to said tongue and projecting adjacent the surface of said disk, a pyrophoric ele- 90

ment carried by said arm, spring pressed against said abradant material whereby operation of the rattle may cause a series of quickened movements of said pyrophoric element over the surface of said abradant material.

LOUIS V. ARONSON.
